JAMES F. CRAVEN, OF PITTSBURGH, PENNSYLVANIA.

METHOD OF MAKING CHAINS.

1,242,325.

Specification of Letters Patent.

Patented Oct. 9, 1917.

Application filed July 14, 1916. Serial No. 109,264.

To all whom it may concern:

Be it known that I, JAMES F. CRAVEN, a resident of Pittsburgh, in the county of Allegheny and State of Pennsylvania, have invented a new and useful Improvement in Methods of Making Chains, of which the following is a specification.

This invention relates to a method of making weldless or solid link chains, by 10 forging the same directly from a bar, thereby dispensing with welding operations.

The object of the invention is to provide a method of making chains of the character described whereby the metal rod or bar 15 is formed into a chain of weldless links without waste of metal, and whereby all of the operations can be effected by means of strong, simple and durable tools acting transversely to the axis of the bar and simultaneously from opposite sides thereof. A 20 further object of the invention is to provide a method for making chains of the kind described in which the tools for effecting the successive operations upon the bar to convert 25 it into a finished chain act simultaneously upon successive links, thereby greatly expediting the transformation of the bar into the chain.

The invention comprises the several 30 method steps hereinafter described and claimed.

In the accompanying drawings, Figure 1 is a diagrammatic view illustrating the manner of transforming the bar into a chain 35 and showing suitable dies for effecting the several operations; Fig. 2 is a plan view of the bar and chain links shown in Fig. 1; Fig. 3 is a transverse section on the line 3—3, Fig. 1; Fig. 4 is a similar section on the 40 line 4—4, Fig. 1; and Fig. 5 is a plan view of one of the second set of dies.

In the drawings, 1 represents a suitable bar from which the chain is formed, said bar preferably being of cruciform cross section, as shown in Fig. 3, having the two pairs of oppositely disposed webs 2, 2 and 3, 3. In transforming this bar into a chain of weldless links, it is subjected to the action of sets of oppositely disposed dies or 45 tools acting simultaneously on opposite faces of said bar, and between successive strokes of said dies or tools the bar is rotated on its axis through an angle of 90°, whereby the dies act on the bar successively 50 in directions at right angles to each other. 55 The first set of dies 4 act by pressure

against the edges of oppositely disposed webs of the bar and are so formed as to indent said webs and entirely separate the same without removing any of the metal and 60 also to press indentations into the core of the bar, and as shown have the central projecting portions 5 which engage the edges of oppositely disposed webs and indent the same, and with curved cavities 6 forwardly 65 and backwardly of the projections 5 and bounded by cheek portions 7 which prevent the metal displaced by the projection 5 from flowing sidewise. The cavities 6 are of substantially the contour of the end portions 8 70 of adjacent links, so that the action of these dies is to entirely separate the top and bottom webs of the bar and also to press indentations 9 into the core of the bar, which indentations almost, but not completely, puncture the same, leaving only thin web portions 10. The extreme ends of the projections 5 are preferably slightly wedge shape, as shown at 11, so as to score the webs 10 at their central longitudinal lines for guiding the next succeeding set of dies. The effect of the dies 4 is to form the bar into successive portions of approximately the shape of crude links, with the metal inclosed by each link quite thin. 85

The next set of dies 12 are of substantially the shape shown in Figs. 1, 4 and 5, the same having projecting portions 13, that of the top die lying on one side of the longitudinal line of the bar being formed, and that of 90 the bottom die lying on the opposite side of said longitudinal line, so that said projecting portions will pass each other as the dies come together, and which projecting portions are pointed so as to puncture the thin 95 webs 10 inclosed by the link, but without removing any of the metal,—said projecting portions toward their bases being widened out and rounded, as shown in Fig. 5, so as to expand the link sidewise and open the 100 same to approximately circular form. The side portions of the dies are provided with semi-circular matching grooves 14 which press the link bar to approximately circular cross section. These dies leave the bar in 105 approximately the form of a chain having circular links, but in which said links are still integrally connected by the fin portions 16.

The fin portions 16 are confined or 110 inclosed by the links so that they are not wholly exposed, and normally can be reached

only by tools applied at an angle of 45° to the plane of the connected links. Tools adapted to act on this connecting fin to sever the same when the links are in normal position are required to be of small size and therefore are neither strong nor durable. In carrying out my method, after the links are formed by the first two sets of dies 4 and 12, one of the links of the connected series, such as the link 17, is shifted relatively to the link 18, to which it is connected, in order to expose the fin 16 to the direct action of a large, simple and strong tool. This shifting is accomplished by moving the exposed link 17 while the remainder of the partially formed links are firmly held in clamps or dies, in a manner to bend or rotate the link 17 around an axis perpendicular to the plane of the link 18, or in other words, twisting the link around its portion 19 which is still integrally attached to the link 18. The extent of this rotation may be varied, but should be not less than 90°, and is shown as rotated through considerably more than 90°, from the dotted line position to the full line position shown in Fig. 2. In this position the fin 16 connecting the two links is exposed from above and below, so that it can be reached by the direct action of a tool working normal to the plane of the bar or chain being formed. This severing tool is shown in the form of a pair of oppositely disposed dies 20, which are provided with sharp projecting edges 21, which pinch through said fin from opposite sides and thus sever the same, the back of said projections being slightly concave so as to round the end portion of the link 18, and the dies at their forward portions being provided with the grooves 23 which forge the severed fin into the end portion of the link 18.

As standard chain links are of oblong form and the links have been opened out to substantially circular form by the dies 12, it is desirable to afterward flatten the links. This can be accomplished by providing the dies 20 with grooves 24 which exert pressure upon the link 17 from above and below, and press the same into oblong form.

The dies 4, 12 and 20 act successively upon different link portions of the partially formed chain, and by direct pressure on opposite sides thereof. Between each of these operations the bar is rotated on its axis through 90°, so that said dies act successively upon portions of the bar at right angles to each other. Since all of these operations are upon successive link portions of the bar and are purely pressing or forging operations upon two opposite sides of the bar, it is possible to mount these three sets of dies upon a single die block or head, and in actual practice all of said dies are actuated by a common pressing head and act

simultaneously upon successive portions of the partially formed bar. By performing these successive steps simultaneously upon successive parts of the bar, the formation of the bar into a chain is greatly expedited, so that a long bar can be worked into a chain at substantially uniform heat throughout the length of the bar.

The several operations will be performed upon the bar while at a good forging heat. The process is entirely a forging or pressure operation, and is effected, as will be observed, without removing or wasting any of the metal, so that the final finished chain will be substantially the same weight as the bar from which it is formed.

When the links are twisted or rotated as above described, in order to expose the connecting fin, that portion of the link which is being turned to one side, which threads down through the link to which it is still connected, can, of course, not rotate and therefore this portion of the link is subjected to twisting or torsional action, which not only affects that portion which threads down through the link to which it is still connected, but also extends somewhat around into the upper and lower portions of the link. The subjection of this portion of the metal to the torsional action increases the tensile strength of the metal, and increases this to the greatest extent at the point where the two links connect to each other, that is, the end portions of the links, and where such links are subjected to the greatest wear and stress and where failure usually occurs. The severing of the connecting fin in the manner described without removing any of the metal also reinforces the end portions of the links by the fact that the metal of the connecting fin is worked into the end portions of the links.

In commercially carrying out the method, it will be performed preferably by automatic machinery in which the bar will be fed forward step by step between the successive strokes of the dies, and also rotated to 90° between successive strokes of the dies. The machine will be so constructed that the unformed bar and partly formed links will be tightly clamped and rigidly held, so that the metal which is displaced by the pressure of the dies, will be caused to flow largely toward the free end, that is, toward the unformed portion of the bar.

If necessary the links after being completely severed can be subjected to further die action in order to smooth them up and reduce any irregularities and fins which may remain, but ordinarily this will not be necessary.

What I claim is:

1. The method of making solid or weldless chain, which consists in taking a suitable bar, indenting the same on opposite

sides by pressure without removing any of the metal to form portions of approximately the shape of chain links, and then puncturing the metal inclosed by the links and opening the same out by pressing the metal sidewise, said indenting and puncturing being effected by lateral pressure in the same plane.

2. The method of making solid or weldless chain, which consists in taking a bar cruciform in cross section, indenting opposite webs by edgewise pressure without removing any of the metal to form portions of approximately the shape of chain links, and then puncturing the metal inclosed by the links and opening the same out by pressing the metal sidewise, said indenting and puncturing being effected by lateral pressure in the same plane.

20 3. The method of making solid or weldless chain, which consists in taking a suitable bar, indenting the same on opposite sides by pressure without removing any of the metal to form portions of approximately the shape of chain links, then puncturing the metal inclosed by the links and opening the same out by pressing the metal sidewise, then shifting two successive links relative to each other around an axis transverse to the bar to expose the connecting fin, and finally severing said fin to separate said links.

4. The method of making solid or weldless chain, which consists in taking a suitable bar and indenting the same from opposite sides by pressure without removing any of the metal to form portions of approximately the shape of chain links, then puncturing by pressing aside the metal inclosed by said links and opening the links out into circular form, then shifting two successive links relative to each other around an axis transverse to the bar to expose the connecting fin, and finally severing said fin to separate said links and simultaneously flatten said circular link to oblong form.

5. The method of making solid or weldless chain, which consists in taking a suitable bar, indenting the same on opposite sides by pressure without removing any of the metal to form portions of approximately the shape of chain links, then puncturing the metal inclosed by the links and opening the same out by pressing the metal sidewise, and finally separating adjacent links, said indenting, puncturing and separating operations being effected by lateral pressure in the same plane.

6. The method of making solid or weldless chain, which consists in taking a suitable bar, indenting the same from opposite sides by pressure without removing the metal

to form portions of approximately the shape of chain links, then puncturing and opening out the links by pressing aside the metal inclosed thereby, then shifting two successive links relative to each other around an axis transverse to the bar to expose the connecting fin, and finally severing said fin to separate said links, said indenting, said puncturing and opening out and said severing of the fin being performed simultaneously upon successive link portions by pressure in the same plane.

7. The method of making solid or weldless chain, which consists in taking a bar cruciform in cross section, indenting opposite webs by edgewise pressure without removing any of the metal to form portions of approximately the shape of chain links, then puncturing the metal inclosed by the links and opening the same out by pressing the metal sidewise, then shifting two successive links relative to each other around an axis transverse to the bar to expose the connecting fin, and finally severing said fin to separate said links.

8. The method of making solid or weldless chain, which consists in taking a bar cruciform in cross section and indenting opposite webs by edgewise pressure without removing any of the metal to form portions of approximately the shape of chain links, then puncturing by pressing aside the metal inclosed by said links and opening the links out into circular form, then shifting two successive links relative to each other around an axis transverse to the bar to expose the connecting fin, and finally severing said fin to separate said links and simultaneously flatten said circular link to oblong form.

9. The method of making solid or weldless chain, which consists in taking a bar cruciform in cross section, indenting opposite webs by edgewise pressure without removing the metal to form portions of approximately the shape of chain links, then puncturing and opening out the links by pressing aside the metal inclosed thereby, then shifting two successive links relative to each other around an axis transverse to the bar to expose the connecting fin, and finally severing said fin to separate said links, said indenting, said puncturing and opening out and said severing of the fin being performed simultaneously upon successive link portions by lateral pressure in the same plane.

In testimony whereof, I have hereunto set my hand.

JAMES F. CRAVEN.
